BICYCLE LAMP

Lee M. Wiley, Marion, Ind., assignor to Delta Electric Company, Marion, Ind., a corporation of Indiana

Application March 27, 1937, Serial No. 133,328

7 Claims. (Cl. 240—7.55)

This invention relates to an electric lamp unit and particularly relates to electric lamp units adapted for use on bicycles.

Certain of the features disclosed in the present application are also disclosed and claimed in the copending application of Lee M. Wiley, Serial No. 80,074 filed May 16, 1936, and the present application is related to said copending application to the extent of the common disclosure therebetween.

Objects of the present invention are to provide an improved unitary lamp structure which may be readily and economically assembled; to provide an improved support or mounting member for a light reflector, battery holder, and an electric switch by which the reflector, the dry cells, and the switch may be secured to the supporting member for mounting within the lamp casing; to provide a lamp structure having an elongated casing and an elongated supporting member mounted therein in spaced relation to the inner walls of the casing, the construction of said elongated mounting member being such that it may be secured to a rivet on said casing adjacent the innermost ends thereof by a simple longitudinal movement to secure said rivet within an open slot in the rear edge of said elongated member; to provide an improved structure whereby the light reflector may be releasably held in position while the lens and retainer ring are being assembled to the casing; and to provide a compact simplified lamp unit attractive in appearance and inexpensive to manufacture.

Other objects of the invention will become apparent from the following specification, the drawing relating thereto, and from the claims hereinafter set forth.

In the drawing, in which like numerals are used to designate like parts in the several views throughout:

Figure 1 is a vertical, longitudinal cross-sectional view, with parts in elevation, of an embodiment of the present invention;

Fig. 2 is a front elevational view taken substantially along the line 2—2 of Fig. 1;

Fig. 3 is a cross-sectional view taken substantially along the line 3—3 of Fig. 1;

Fig. 4 is a cross-sectional view taken substantially along the line 4—4 of Fig. 1;

Fig. 5 is a longitudinal side elevational view of a unitary supporting or mounting means embodying features of the present invention;

Fig. 6 is a fragmentary top plan view taken substantially along the line 6—6 of Fig. 5;

Fig. 7 is a fragmentary plan view taken substantially along the line 7—7 of Fig. 5; and

Fig. 8 is a fragmentary top plan view taken substantially along the line 8—8 of Fig. 5.

According to the present invention an independent lamp structure for mounting on bicycles dispenses with the necessity of separated parts and cumbersome wiring by providing a unitary supporting or mounting means for mounting the light reflector, the dry cells, and the switch which may be assembled and secured to the casing in an improved manner. The improved supporting or mounting means includes an elongated substantially cylindrical main body portion which is of a resilient material and is slotted throughout its length for supporting therein dry cells. The dry cells may be removed from the supporting member mounted within the casing in the manner described and claimed in the copending application referred to above.

The supporting member also has formed integral therewith a longitudinal extension adjacent the inner edge which is provided with an open or U-shaped slot at its edge and which is provided with openings therethrough for mounting thereon an electric switch. An electric switch may be mounted and secured to the holder or mounting member before its assembly within the casing. By providing an open or U-shaped slot within the rear edge of the extension, which cooperates with a shouldered rivet secured to the casing with the shoulder spaced from the inner walls of the casing, the supporting member with the switch mounted thereon may be assembled within the casing by slidably engaging the shoulder rivet with the extension within the open slot.

According to the present invention means are also provided whereby the reflector may be held in position on the unitary supporting or mounting member while the lens and retainer ring are being assembled to the casing. This means includes lugs formed on the reflector for removable reception within slots provided adjacent the front edge of the mounting member.

For a better understanding of the invention, reference may be had to the accompanying drawing in which an embodiment of the present invention is illustrated in detail. An electric lamp unit, generally indicated at 17, comprises a main body casing or shell which is made up of an upper section 18 and a lower section 19, each section being substantially semi-circular in shape in transverse section and being joined along their horizontally disposed edges so that transverse sections of the assembled sections forming the 55

main body portion or shell are substantially circular in form. The sections are extremely long and are curved longitudinally gradually tapering toward the rear to give a stream-lined effect and 5 to close the rear end, the casing terminating in an opening in the front end. The lower section has an outwardly and horizontally formed flange 20 extending therearound and the upper section has an outwardly extending flange 21 of greater 10 length than the flange 20, the flange 21 being rolled over and clamped to the flange 20, as best shown in Fig. 4, to form a horizontal fin or bead around the head portion of the lamp unit and rigidly securing the two sections together. The 15 front edge portion of the sections 18 and 19 are offset inwardly around the periphery thereof at 25 to provide a seat for the front or retaining ring portion 28 when the sections are assembled.

As disclosed in the copending application referred to, when dry cells become exhausted they 20 very often expand, and if they initially fit their holder with any degree of tightness, upon expansion they will become more tightly held within the holder often freezing therein and making 25 it exceptionally difficult to remove them when it is desired to insert new batteries. Since it is desirable that the dry cells be securely held in position at all times, a resilient holder which will 30 securely hold the cells when initially placed therein but which will permit their expansion upon exhaustion and yet permit ready removal of the exhausted dry cells is provided.

It is evident that as the present invention is directed to a lamp unit which is relatively small 35 in size that assembly of the elements making up the unit is a difficult problem, as relatively small spaces are available for the reception and manipulation of tools for securing the parts relative to each other. The present invention provides a structure by which the construction and 40 assembly of the elements to provide the unitary lamp structure are relatively simple.

According to the present invention a unitary mounting or supporting member generally indicated at 30 is provided for mounting a lamp reflector 32, dry cells 34, and an electric switch element 36. The holder or mounting member 30 comprises an elongated substantially cylindrical resilient sheet metal member 38 having a longitudinally extending slot 40 throughout its length. Dry cells 34 are resiliently and removably held 45 in the cylindrical portion 38; and in the illustration shown two dry cells in series are mounted within the holder, but it is to be understood that the holder may be of such a size and length that any desired number of dry cells may be mounted 50 therein. By constructing the holder of resilient or readily yieldable material and providing the slot 40 it can be seen that upon expansion of the exhausted dry cells that they may be removed 55 without undue binding within the holder.

A longitudinal extension 42 is formed integral with the cylindrical member 38 adjacent the rear and lower end thereof, the extension 42 being 60 formed to conform to the shape of the shell contacted by the extension when the parts are assembled. The extension member 42 is provided with an open or U-shaped slot 44 in its rear edge for securing the holder 30 to the casing at the 65 rear edge. A shouldered rivet 46 is secured to the casing 19 with the shoulder of the rivet inwardly spaced from the inner wall of the casing member for reception within the open slot 44 70 when the holder is mounted within the casing. 75

The shoulder of the rivet thus engages the upper surface of the extension 42 within the slot 44.

The electric switch element 36 is mounted to the extension 42 by means of rivets 48, or the like, which extend through openings 50 provided in the extension. Another opening 52 is provided through the extension 42 to receive therethrough the shiftable button 54 of the switch 36. The opening 52 is of course of such a length as to permit shifting of the button 54 within the opening. The switch 36 is thus secured to the extension member 42 before mounting the holder 30 within the casing which is a relatively simple operation. When mounted within the casing the button extends through an opening in the casing 15 corresponding to the opening 52.

In order to removably mount the reflector 32 to the mounting member 30, a J-shaped slot 56 is provided in the front edge of the holder 30 with the edge opening of the slot substantially diametrically opposed to the front edge opening of the elongated slot 40. Another slot 57 is provided in the holder 30 adjacent the front edge thereof, the slot 57 opening into the elongated slot 40 at substantially right angles thereto. These slots 25 thus provide for removably mounting the reflector 32 to the holder in a manner to be described.

The reflector 32 is preferably so constructed that it may be mounted in an offset relationship 30 to the horizontal center line of the casing unit, so that the light beams reflected therefrom will be directed downwardly to form a bright spot in front of the bicycle close to the lamp when the lamp is mounted on the bicycle with its center 35 line in a substantially horizontal plane. This is accomplished preferably by constructing an extension 58 on the front of the main parabolic section 60 of the reflector, the extension extending around the front periphery of the parabolic 40 section, having its greatest width at the bottom and gradually diminishing in width to a point at the top. The reflector 32 is provided with rearwardly and radially inwardly extending lugs 45 62 and 64 which are formed on the reflector 32 in diametrically opposed relation. The lugs 62 and 64 are of such a width that they may be received within the front edge opening of the slots 56 and 40 respectively, and upon a slight turning movement the lugs are held within that portion 50 of the slot 56 parallel with the front edge of the member 30 and the slot 57 respectively. The openings through the front edge formed by the slots 40 and 56 respectively are preferably of different widths, with the lugs 64 and 62 having 55 correspondingly different widths so as to prevent the user, or one assembling the lamp unit, from getting the offset reflector assembled in place upside down.

In order to support the holder 30 within the 60 casing adjacent the front thereof and to support the holder in spaced relation to the walls of the casing, a bracket portion 66 is formed integral with the holder 30 and downwardly offset therefrom. The bracket member 66 may then be secured to the casing by means of the rivet 68 or the like.

The details of the switch 36 per se are disclosed in the copending application referred to above, 70 and the switch is preferably located between the batteries and the shell in the ground circuit. The switch comprises a U-shaped contact spring element 70 which is rigidly secured at one end to one end of a switch terminal 72 in electrical con-

tact therewith and is in resilient engagement at the other end of the spring with one of the terminals of the rearmost battery 34. The spring 70 tends to force the batteries forwardly and will 5 take up any looseness in the assembly by forcing the batteries forwardly and maintain contact between the circuit elements.

The electric circuit may be traced from the batteries through one end of the lamp filament of the 10 lamp 33 and out of the other end of the filament to the lamp base, through the metallic reflector unit to the holder 38, and from the holder 38 to the casing. The circuit is completed through the switch which is also grounded to the casing, and 15 through the spring contact 70 to one terminal of the batteries.

A lens 74, preferably of the unbreakable type, has an inwardly offset edge portion around its outer periphery which is tightly held between the 20 forward edge of the annular ring 28 and the front annular edge of the reflector when the parts are assembled.

Suitable means may be provided to rigidly mount the lamp casing unit upon the bicycle and 25 in the embodiment illustrated a single stud 78 is attached to the lamp casing and is adapted to project through an opening in the mud guard. A nut 80 is provided for engagement with the under side of the guard and the stud to securely hold the 30 unit in position on the guard.

From the above it is evident that the present invention provides a simplified structure whereby the elements providing the unitary lamp may be conveniently and more economically constructed 35 and assembled. By the provision of the unitary mounting or holding member 30 the switch element 36 may be secured to the holder before insertion within the casing; and by the provision of the open slot 44 and the rivet 46 the holder may 40 be mounted within the casing by a simple longitudinal sliding movement by which the rivet is engaged within the slot 44. Further the provision of the removable mounting on the reflector 32 to the holder 30 provides a simplified means for retaining the reflector in position while the lens and 45 retainer ring are being assembled to the case.

Formal changes may be made in the specific embodiment of the invention illustrated without departing from the spirit and substance of the invention, the scope of which is commensurate with the appended claims.

What is claimed is:

1. An electric bicycle lamp unit comprising an elongated casing, an elongated substantially cylindrical dry cell holder mounted within said casing longitudinally thereof, and means supporting said dry cell holder in spaced relation to the walls of said casing, said last named means including a longitudinal extension on the rear end of 55 said holder, said extension having an open slot adjacent its rear edge for engagement with a securing means on said casing.

2. An electric bicycle lamp unit comprising an elongated casing, an elongated substantially cylindrical dry cell holder mounted within said casing longitudinally thereof, means securing said holder to said casing including a shoulder rivet 60 secured to said casing with the shoulder thereof spaced from the wall of said casing, and means

forming an open slot secured to said holder for engagement with said rivet.

3. An electric bicycle lamp unit comprising an elongated casing, an elongated substantially cylindrical dry cell holder mounted within said casing longitudinally thereof, means supporting said holder in spaced relation to the walls of said casing, said means including a bracket member formed integral with said holder and secured to said casing adjacent the front thereof and a rearward extension formed integral with the rear of said holder, said extension having a U-shaped slot adjacent the rear edge thereof, and means secured to said casing for engagement with said extension within said slot. 5

4. An electric bicycle lamp unit comprising an elongated casing, an elongated substantially cylindrical dry cell holder mounted within said casing longitudinally thereof, said holder being resilient and being slotted longitudinally thereof to 10 permit expansion and ready removal of exhausted dry cells held therein, means supporting said holder in spaced relation to the walls of said casing, said last named means including a rearwardly directed extension on said holder having a U- 15 shaped slot adjacent the rear edge thereof, and means secured to said casing received within said slot for securing said holder to said casing. 20

5. An electric bicycle lamp unit comprising an elongated casing, an elongated substantially cylindrical supporting member mounted within said casing longitudinally thereof, said member being resilient and being slotted to permit expansion and ready removal of exhausted dry cells held 25 therein, means supporting said supporting member in spaced relation to the walls of said casing, said last named means including a longitudinal extension on said supporting member, an electric switch secured to said extension, a light reflector, 30 means removably securing said reflector to said supporting member, and means secured to said casing securing said extension to said casing. 35

6. A unitary mounting member for a reflector, a dry cell, and an electric switch comprising an elongated substantially cylindrical member, said member being resilient and being slotted throughout its length, a longitudinal extension secured to one end of said member, a J-shaped slot through 45 said member adjacent the other end thereof substantially diametrically opposed to said first named slot, and another slot adjacent said last named end said last named slot opening into said first named slot. 50

7. A unitary mounting member for a reflector, a dry cell, and a switch, comprising an elongated substantially cylindrical member, said member being resilient and being slotted throughout its length, a longitudinal extension having mounting 55 openings therethrough for an electric switch secured to one end of said holder, a J-shaped slot opening through the other edge of said member substantially diametrically opposed to said first named slot, the width of said first named slot being different from the width of the opening through the front edge of said last named slot, and another slot adjacent said last named end said last named slot opening into said first named slot. 60
